MOUNT FOR MACHINE GUNS

John M. Ewart, Beverly, Mass., assignor to United
Shoe Machinery Corporation, Flemington, N. J.,
a corporation of New Jersey

Application February 14, 1944, Serial No. 522,325

16 Claims.

(Cl. 89—37)

1

This invention relates to ordnance mounts and more particularly to a mount for a plurality of machine guns. As herein illustrated the invention is shown as embodied in a mount for two .50 caliber Browning machine guns, but it is to be understood that the invention is of broader utility and may be used with other makes of guns or in mounts for more or less than two guns.

Machine guns of the type above mentioned are commonly provided near their back ends with a pair of apertured ears and near their front ends with a pair of oppositely disposed threaded attaching bosses which are used for securing the guns to an adaptor or equivalent supporting structure. Objects of this invention are to provide a novel and improved gun mount for accommodating machine guns of this type in which the guns can be readily installed and which are so arranged that adjustments for bore-sighting are facilitated and displacement of the guns for servicing made possible without disturbing previously made bore-sighting adjustments. With these ends in view, and in accordance with a feature of this invention, the adaptor is provided with separate mounting means for cooperating with the threaded attaching bosses at the front end of a machine gun and with the apertured ears at its back end to support it on the adaptor, each of the supporting means being adapted for ready attachment to the aforementioned parts of the gun and capable of imparting adjusting movements in different directions thereto. More particularly, the mounting means for cooperating with the threaded attaching bores comprises a yoke-like member rotatably mounted in the adaptor and having threaded members associated therewith for pivotally and adjustably securing the front end of the gun thereto. The mounting means for cooperating with the apertured ears, in accordance with a further feature of the invention, comprise carriage members adapted slidably and pivotally to support the back end of the gun and also arranged for adjustment laterally of the adaptor for bore sighting. These carriage members are furthermore provided with means for locking them in adjusted position, as well as with threaded means for facilitating adjusting movements thereof; the threaded means also serving as a stop for relocating the gun after displacement for servicing or removal for repair. For slidably and pivotally mounting the back end of the guns these carriage members have formed in them guideways having oppositely facing walls, for receiving trunnion blocks on which the apertured ears of the guns are rotatably mounted and,

2

in accordance with a further feature of this invention, means are provided for varying the distance between these oppositely facing walls to take up for wear and also to accommodate manufacturing variations in the distance between the outside faces of these ears.

The above and other objects and features of the invention will appear in the following detailed description of the preferred embodiment thereof shown in the accompanying drawings and will be pointed out in the claims.

In the drawings,

Fig. 1 is a plan view of a machine-gun mount embodying this invention;

15 Fig. 2 is a sectional view of the mount taken on the line II—II of Fig. 1, looking in the direction of the arrows, and showing certain of the parts in elevation;

Fig. 3 is a sectional view of the mount taken on 20 the line III—III of Fig. 1.

Referring to the drawings, in which the invention is shown embodied in a mount for two machine guns, the reference character 10 designates an adaptor comprising an elongated hollow box-like structure formed of welded sheet metal and having side walls 12, 12, top and bottom plates 16, 16, and lateral members 18, 18. At the right-hand end of the adaptor, as viewed in Fig. 1, the top and bottom plates are extended, as indicated 25 at 20, 20, to provide supports for hand grips 22, 22, a cross brace 24 being provided to strengthen the assembly at this point. In use the adaptor is pivotally mounted, for movement of the guns in elevation, on the top of a suitable support 26, having a bifurcated upper end, by means of a pivot pin 28; the support 26 being itself rotatable for swinging the adaptor, and the guns carried thereby, in azimuth.

Near the front end of the adaptor there is a 30 bushing 30 having flanges 32, 32 against which the side walls 12, 12 bear, and a through-and-through bore 34 in which are mounted two yoke members 36, 36. These yoke members are held in place in the bushing by means of a bolt 40 having a castellated lock nut 42 which draws thrust shoulders 44, 44 on the yoke members against the ends of the bushing 30. The lock nut 42 is tightened just enough to take up all looseness while still permitting rotation of the yoke members within the bushing on cylindrical end portions 46, 46 on these members and a cotter pin 45 being provided to hold it in adjusted position. Secured to the bottom side of the adaptor, somewhat to the rear of its middle portion, is a laterally extending crossbar 50, formed out of a chan-

nel-shaped piece of metal which projects outwardly beyond each side of the adaptor.

The guns, indicated by the reference characters 52, 52, which the adaptor is designed to support, are of a known type and are each provided adjacent to their front ends with a recoil sleeve 54 having oppositely positioned threaded supporting bosses 56, 56. At its back end, each gun has two downwardly projecting ears 58, 58, likewise intended for supporting purposes, and these ears are each provided with a bore 60.

Slidably mounted on each of the projecting ends of the crossbar 50 is a carriage 62 having a flat bottom face 64 and two downwardly turned guide flanges 66, 68, Figs. 1 and 2. For holding each carriage in any desired position of adjustment on the crossbar 50, a clamping bolt 70, having a nut 72 and a lock nut 74, is provided, and these clamping bolts pass through elongated slots 76, 76, in the ends of the crossbar. The nuts 72 bear against filler blocks 78 interposed between them and the bottom of the crossbar 50. Each carriage is provided with oppositely facing lengthwise guideways, or grooves, having side and bottom faces 82 and 84, respectively.

The ears 58, 58 on each of the guns are rotatably mounted on a trunnion shaft 90, received in the bores 60, 60 and having ends 92 of reduced diameter that project into trunnion blocks 94, 94. These blocks, which are held loosely on the ends of the trunnion shafts by cotter-pins 95, are of such a size as to have a nice sliding fit between the side faces 82, 82 of the grooves in the carriages 62 and are further provided with arcuately shaped end faces 96 for engaging the bottom faces 84 of these grooves. The bottom face 84 of the outside groove on each of the carriages is formed by the side of a wedge-shaped block 98 having an inclined surface 100 which bears against a similarly inclined face 102 on the carriage. Each of the wedge blocks 98 has secured to it a threaded stud 104 which projects outwardly through an elongated slot 106 in the carriage and on this stud is a wedge locking nut 108. As will be apparent, when the nut 108 is loosened the wedge block may be shifted laterally of the carriage in such a way as to increase or decrease the distance between the bottom faces 84, 84 of the carriage grooves. Normally the wedge blocks are so adjusted that the arcuate ends 96, 96 of the trunnion blocks have a nice sliding fit between the bottom faces 84, 84 of the grooves, and the blocks themselves bear snugly against the outside surfaces of the ears 58, 58. The distance between the shoulders 93, 93, formed by the reduced ends 92, 92, on the trunnion shafts 90, is somewhat less than the distance between opposite faces of the ears 58, 58 and enough less so that the blocks 94, 94 will bear on the outside surfaces of these ears without striking the shoulders. The trunnion shafts 90 are short enough to clear the bottom faces 84, 84 of the grooves. This arrangement makes it possible to accommodate such variations in the distance between the outside surfaces of the ears 58, 58 as may be encountered in different guns by suitable adjustment of the wedge blocks 98.

The yokes 36 are each provided with aligned threaded bores 110, 110 in which are mounted bored externally threaded gun-adjusting screws 112, 112 and fitted within these screws are gun-clamping screws 114, 114, each having an inner end 116, threaded into a boss 56 of the recoil sleeve, and a head 117 which bears against the outer end of a gun-adjusting screw 112. Lock nuts 118 are provided for locking the gun-ad-

justing screws 112 in adjusted position. Each of the carriages 62 has at its outer end a downwardly turned flange through which is threaded a stop screw 120 provided with a lock nut 122.

Adjacent to one of the hand grips 22 there is mounted on the adaptor a trigger 130 which operates through a mechanical linkage, including rollers 132, 132 for engaging the gun sears 134, 134 to fire the guns. A safety lock, indicated generally by the reference character 136, is also provided.

Referring to Figs. 1 and 3, each recoil sleeve 54 is slidably mounted on an inner sleeve member 140 that is threaded onto a forwardly projecting cylindrical portion 142 of the gun. This cylindrical portion is bored to slidably receive the gun barrel 144 and its surrounding jacket 146. Springs, not shown, are arranged between the inner sleeve 140 and the recoil sleeve 54 to cushion the recoil when the gun is fired by permitting a slight rearward movement of the body of the gun with respect to the recoil sleeve 54. This rearward movement of the body of the gun is accommodated by the sliding of the trunnion blocks 94, 94 in their guideways.

In Fig. 1 the uppermost gun is shown in position for use, while the lowermost gun is illustrated in an intermediate position which it will assume either when being mounted on, or removed from, the adaptor. In removing either of the guns, the clamping screws 114, 114, on the corresponding yoke 36, and nuts 72 and 74 on bolt 70 are loosened to permit the back end of the gun to be moved out to the position in which the lowermost gun in Fig. 1 is shown, carriage 62 sliding out until the bolt 70 comes to the end of the slot 76 and the clamping screws 114 turning in the bores of the gun-adjusting screws 112, 112. The curvature of the arcuate ends 96 of the trunnion blocks 94 is sufficient to permit this without binding in the carriage grooves. The clamping screws 114, 114 may now be unscrewed from the recoil sleeve 54 and the gun removed from the adaptor by first swinging its front end out far enough to clear the yoke 36 and then sliding the gun forwardly until the blocks 94, 94 are free from their grooves in the carriage 62.

In placing a gun in the adaptor the above procedure is reversed, i. e., the trunnion blocks 94 are inserted in the grooves in the carriage 62, and then the front end of the gun with its recoil sleeve is swung in so as to bring the threaded bosses 56, 56 on the recoil sleeve 54 into alignment with the gun-adjusting screws 112. Now, after the clamping screws 114, 114 have been threaded into the recoil sleeves loosely, the back end of the gun is swung in to the position in which the uppermost gun in Fig. 1 is shown and until the stop screw 120 bears against the outer end of the crossbar 50. Nuts 72 and 74 may now be tightened, the wedge block 98 adjusted, and the lock nut 108 tightened. The front end of the gun is next made secure by turning the gun-adjusting screws 112, 112 down against the faces of the bosses 56, 56, tightening the lock nuts 118, 118, and finally tightening the gun-clamping screws 114, 114.

Bore-sighting adjustments of the guns are made in the following manner. To adjust a gun in elevation, the gun-clamping screws 114, 114 and lock nuts 118, 118 are first loosened and then, by suitable turning of the gun-adjusting screws 112, the front end of the gun may be raised or lowered until the desired sighting in elevation is obtained, whereupon the lock nuts 118 are again

tightened. During this adjustment the gun pivots at its rearmost end on the trunnion shaft 90 and the yoke 36 turns slightly in the bushing 30 enough to accommodate itself to the higher or lower position of the front end of the gun and to avoid binding of the gun-adjusting and gun-clamping screws. In adjusting a gun in azimuth, the gun-clamping screws 114, 114 and nuts 72 and 74 are loosened and the lateral position of the back end of the gun is changed by sliding the carriage 62 along on the crossbar 50 until the desired sighting in azimuth is obtained. To facilitate this adjustment the stop screw 120 may be employed in the following manner. With the lock nut 122 loosened this stop screw is backed off away from the end of the crossbar 50 and a rough adjustment of the back end of the gun in azimuth is made. The screw 120 is now turned until its end touches the end of the crossbar 50, after which the continued turning of the screw in one direction or another, while its end is held against the crossbar 150 by inward pressure against the carriage 62, will give a fine adjustment of the gun in azimuth.

The stop screw 120 makes it possible to service either one of the guns without disturbing its bore-sighting adjustment, since the gun to be serviced may be moved to the position shown in the lower part of Fig. 1, merely by loosening the gun-clamping screws 114, 114, which does not disturb the setting of the gun-adjusting screws 112, 112, and the nuts 72 and 74. In this position, the back plate assembly of the gun, indicated in general by the reference character 150, may be removed. After servicing, the back end of the gun is moved back to its former adjusted position, as determined by the engagement of the stop screw 120 with the outer end of the crossbar 50, and the gun-clamping screws 114, 114 and nuts 72 and 74 retightened. Although not usually necessary for servicing, the gun may be entirely removed from the adaptor, without altering the setting of the gun-adjusting screws 112 or the stop screw 120, and then replaced without disturbing its previous bore-sighting adjustments.

Having described my invention, what I claim as new and desire to secure by Letters Patent of the United States is:

1. A mount for two machine guns comprising an adaptor, a pair of yoke members rotatably mounted on the adaptor, means for pivotally and adjustably mounting the front ends of a pair of machine guns on the yoke members, a pair of carriage members adjustably mounted on the adaptor, and means associated with the carriage members for slidably and pivotally supporting the back ends of said machine guns.

2. A mount for machine guns comprising an adaptor, a yoke member rotatably mounted on the adaptor, means for pivotally and adjustably mounting the front end of a machine gun on the yoke member, a carriage member adjustably mounted on the adaptor in spaced relation to the yoke member, and means associated with the carriage member for pivotally and slidably supporting the back end of said machine gun.

3. A mount for two machine guns of the type having oppositely positioned threaded attaching bosses adjacent its front end and apertured ears adjacent its back end comprising an adaptor, a pair of yoke members rotatably mounted on the adaptor, means adapted to engage the threaded attaching bosses of a pair of machine guns for adjustably and pivotally securing the front ends of the machine guns to said yoke members, and

means on the adaptor for engaging the apertured ears of said machine guns to slidably and adjustably secure the back ends of the guns to the adaptor.

4. A mount for a machine gun of the type having oppositely positioned threaded attaching bosses adjacent their front ends and apertured ears adjacent their back ends comprising an adaptor, a yoke member rotatably mounted on the adaptor, means adapted to engage the threaded attaching bosses of a machine gun for adjustably and pivotally securing the front end of the gun to the yoke member, and means on the adaptor for engaging the apertured ears of said machine gun to slidably and adjustably secure the back end of the gun to the adaptor.

5. A mount for two machine guns of the type having oppositely positioned threaded attaching bosses near its front end and apertured ears adjacent its back end comprising an adaptor, a pair of yoke members rotatably mounted on the adaptor, a pair of aligned threaded openings in each yoke member, a bored adjusting screw in each of the threaded openings, and a gun-clamping screw received in each of the adjusting screws for engaging the threaded attaching bosses of a pair of machine guns pivotally to secure them to the yoke members, and means on the adaptor cooperating with the apertured ears of the guns for adjustably and slidably supporting the back ends of the guns.

6. A mount for machine guns of the type having oppositely positioned threaded attaching bosses near their front ends and apertured ears adjacent their back ends comprising an adaptor, a yoke member rotatably mounted on the adaptor, a pair of aligned threaded openings in the yoke member, a bored adjusting screw in each of the threaded openings, and a gun-clamping screw received in each of the adjusting screws for engaging the threaded attaching bosses of a machine gun pivotally to secure it to the yoke member, and means on the adaptor cooperating with the apertured ears of the gun for adjustably and slidably supporting the back end of the gun.

7. A mount for two machine guns of the type having oppositely positioned threaded attaching bosses near its front end and apertured ears adjacent its back end comprising an adaptor, a pair of yoke members rotatably mounted on the adaptor, means carried by the yoke members adapted to engage the threaded attaching bosses of a pair of machine guns for adjustably and pivotally securing them to the adaptor, a supporting member secured to the adaptor in spaced relation to the yoke members and having ends that project laterally beyond the opposite sides of the adaptor, carriage members mounted on each end of the supporting member for adjustment laterally of the adaptor, and means associated with the carriage members and adapted to cooperate with the apertured ears of said machine guns for slidably and pivotally supporting their back ends on the adaptor.

8. A mount for machine guns of the type having oppositely positioned threaded attaching bosses near their front ends and apertured ears adjacent to their back ends comprising an adaptor, a yoke member rotatably mounted on the adaptor, means carried by the yoke member adapted to engage the threaded attaching bosses of a machine gun for adjustably and pivotally securing its front end to the adaptor, a supporting member secured to the adaptor in spaced

relation to the yoke member and having an end that projects laterally beyond one side of the adaptor, a carriage member mounted on the supporting member for adjustment laterally of the adaptor, and means associated with the carriage member and adapted to cooperate with the apertured ears of said machine gun for slidably and pivotally supporting its back end on the adaptor.

9. A mount for two machine guns of the type having oppositely positioned threaded attaching bosses near their front ends and apertured ears near their back ends comprising an adaptor, a pair of yoke members rotatably mounted in the adaptor, means carried by the yoke members adapted to engage the threaded attaching bosses of a pair of machine guns for adjustably and pivotally securing them to the adaptor, a supporting member secured to the adaptor in spaced relation to the yoke members and having ends that project laterally beyond the opposite sides of the adaptor, carriage members mounted on each end of the supporting member for adjustment laterally of the adaptor, oppositely facing guideways on the carriage members, and means associated with these guideways adapted to cooperate with the apertured ears of said machine guns for slidably and pivotally supporting their back ends on the adaptor, said means including trunnion blocks slidable in the guideways.

10. A mount for machine guns of the type having oppositely positioned threaded attaching bosses near their front ends and apertured ears near their back ends comprising an adaptor, a yoke member rotatably mounted in the adaptor, means carried by the yoke member adapted to engage the threaded attaching bosses of a machine gun for adjustably and pivotally securing it to the adaptor, a supporting member secured to the adaptor in spaced relation to the yoke member and having an end that projects laterally beyond one side of the adaptor, a carriage member mounted on the supporting member for adjustment laterally of the adaptor, oppositely facing guideways on the carriage member, and means associated with the guideways adapted to cooperate with the apertured ears of said machine gun for slidably and pivotally supporting its back end on the adaptor, said means including trunnion blocks slidable in the guideways.

11. A mount for two machine guns of the type having oppositely positioned threaded attaching bosses near their front ends and apertured ears near their back ends comprising an adaptor, a pair of yoke members rotatably mounted on the adaptor and provided with means for engaging the threaded attaching bosses of a pair of machine guns to secure them thereto, a supporting member mounted on the adaptor in spaced relation to the yoke members and having ends that project laterally beyond the opposite sides of the adaptor, carriage members mounted on each end of the supporting member for adjustment laterally of the adaptor, trunnion blocks, guideways having oppositely facing walls formed on said carriage members for slidably receiving the trunnion blocks, and means for rotatably mounting the apertured ears of said machine guns on said blocks, said carriage members being provided with means for varying the distance between the oppositely facing walls of its guideways.

12. A mount for machine guns of the type having oppositely positioned threaded attaching bosses near their front ends and apertured ears near their back ends comprising an adaptor, a

yoke member rotatably mounted on the adaptor and provided with means for engaging the threaded attaching bosses of a machine gun to secure it thereto, a supporting member mounted on the adaptor in spaced relation to the yoke member and having an end that projects laterally beyond one side of the adaptor, a carriage member mounted on the supporting member for adjustment laterally of the adaptor, trunnion blocks, guideways having oppositely facing walls formed on said carriage member for slidably receiving the trunnion blocks, and means for rotatably mounting the apertured ears of the machine gun on said blocks, said carriage member being provided with means for varying the distance between the oppositely facing walls of its guideways.

13. A mount for two machine guns of the type having oppositely positioned threaded attaching bosses near their front ends and apertured ears near their back ends comprising an adaptor, a pair of yoke members rotatably mounted on the adaptor and provided with means for engaging the threaded attaching bosses of a pair of machine guns to secure it thereto, a supporting member mounted on the adaptor in spaced relation to the yoke members and having ends that project laterally beyond the opposite sides of the adaptor, carriage members mounted on each end of the supporting member for adjustment laterally of the adaptor, trunnion blocks, guideways having oppositely facing walls formed on said carriage members for slidably receiving the trunnion blocks, means for rotatably mounting the apertured ears of said machine guns on said blocks, and means comprising wedge blocks associated with each carriage member for varying the distance between the oppositely facing walls of its guideways.

14. A mount for machine guns of the type having oppositely positioned threaded attaching bosses near their front ends and apertured ears near their back ends comprising an adaptor, a yoke member rotatably mounted on the adaptor and provided with means for engaging the threaded attaching bosses of a machine gun to secure it thereto, a supporting member mounted on the adaptor in spaced relation to the yoke member and having an end that projects laterally beyond one side of the adaptor, a carriage member mounted on the supporting member for adjustment laterally of the adaptor, trunnion blocks, guideways having oppositely facing walls formed on said carriage member for slidably receiving the trunnion blocks, means for rotatably mounting the apertured ears of said machine gun on said blocks, and means comprising wedge blocks associated with the carriage members for varying the distance between the oppositely facing walls of its guideways.

15. A mount for two machine guns of the type having oppositely positioned threaded attaching bosses near their front ends and apertured ears near their back ends comprising an adaptor, a pair of yoke members rotatably mounted on the adaptor and provided with means for engaging the threaded attaching bosses of a pair of machine guns to secure them thereto, a supporting member mounted on the adaptor in spaced relation to the yoke members and having ends that project laterally beyond the opposite sides of the adaptor, carriage members mounted on each end of the supporting member for movement laterally of the adaptor, means for securing the carriage members in adjusted position on the supporting

member, threaded means for moving the carriage members, and means associated with the carriage members for cooperating with the apertured ears of the machine guns for supporting them on the adaptor.

16. A mount for machine guns of the type having oppositely positioned threaded attaching bosses near their front ends and apertured ears near their back ends comprising an adaptor, a yoke member rotatably mounted on the adaptor provided with means for engaging the threaded attaching bosses of a machine gun to secure it thereto, a supporting member mounted on the

adaptor in spaced relation to the yoke member and having an end that projects beyond the side of the adaptor, a carriage member mounted on the supporting member for movement laterally of the adaptor, means for securing the carriage member in adjusted position on the supporting member, threaded means for moving the carriage member, and means associated with the carriage member for cooperating with the apertured ears of the machine gun for supporting it on the adaptor.

JOHN M. EWART.
